TILTING DOOR ASSEMBLY

Lowell V. Robinson, Detroit, Mich., assignor to
Crawford Door Company, Detroit, Mich., a corporation of Michigan

Application October 19, 1946, Serial No. 704,414

1 Claim. (Cl. 20—16)

1.

This invention relates to a door assembly actuated by a spring-impelled toggle mechanism to swing from a closed vertical position to a horizontal open position. Specifically the invention deals with a tilting garage door pivotally suspended at its upper corners and counterbalanced by spring-impelled toggle arms.

According to this invention a one-piece closure member, such as a door, is swingably suspended on horizontally aligned pivots at the top portion of the closure. Pivoted-together toggle arms are respectively pivoted to the closure and to fixed pivots spaced beneath the horizontally aligned pivots. Tension springs are mounted between the horizontally aligned pivots and the pivotal connections between the arms. These springs urge the arm pivots toward the horizontally aligned closure suspension pivots to thereby swing the arms into open position and move the closure from a vertical closed position to a horizontal open position. In the open position, the closure can extend outwardly from a doorway or other opening closed thereby to form a canopy for the opening.

While the invention will hereinafter be specifically described as embodied in a tilting garage door assembly, it should be understood that the principles of the invention are generally applicable to closures of any nature, and the invention is, therefore, not limited for use with garage doors.

It is an object of the invention to provide a tilting door construction actuated by spring-impelled toggles.

Another object of the invention is to provide a tilting door assembly having door jamb-carried horizontally aligned pivots for the upper corners of the door together with spring-impelled toggle arms operating between the door jambs and the door in spaced relation from the tilting axis of the door.

Another object of the invention is to provide a tilting garage door which is counterbalanced by means of pivotally connected arms carried respectively on pivots by the door jambs and the door in spaced relation from the tilting axis of the door.

Other and further objects of the invention will be apparent to those skilled in the art from the following detailed description of the annexed sheets of drawings which, by way of a preferred example only, illustrate one embodiment of the invention.

On the drawings:

Figure 1 is a broken inside elevational view of a door assembly according to this invention.

2

Figure 2 is a vertical cross-sectional view, with parts in end elevation, of the door assembly of Figure 1 illustrating the door in opened position.

Figure 3 is a fragmentary cross-sectional view, with parts in elevation and parts broken away, taken along the line III—III of Figure 1.

Figure 4 is a fragmentary enlarged view, with parts in vertical cross section, of the toggle arm arrangement for the door assembly.

10. Figure 5 is a horizontal cross-sectional view taken along the line V—V of Figure 1.

As shown on the drawings:

In Figures 1 and 2, the reference numeral 10 designates generally a door assembly having a doorway 11 defined by side door jambs 12, 12, a top lintel 13, and a bottom floor 14. This doorway 11 is closed by a door 15. The door 15 can be of any desired one-piece construction. The illustrated door is composed of a sheet 16 of aluminum having longitudinally extending rigidifying beads 16a embossed therein. Z-beams 17, 17 are secured to the inner face of the door at the side edges thereof to provide end stiles. As shown in Figure 5, the Z-beam has a flange 17a extending outwardly from the web 17b thereof which defines the side edge of the door. These flanges 17a are arranged to thrust against the door jambs 12, 12 carried by the door casings 18. Similar Z-beams 19 and 20 are secured on the top and bottom ends of the sheet 16 and further rigidify the door. Intermediate Z-beams such as 21 can be riveted to the sheet metal 16 to extend vertically as shown.

Brackets 22 are riveted to the inner faces of 35 the door 15 at the upper corners thereof, preferably on the Z-beams 17 and 19. These brackets 22 have flanges 22a normal to the plane of the door as shown. Brackets 23 are secured to the inner faces of the door jambs 12 and have flanges 40 23a extending inwardly from the jambs. Pivot pins 24 extend through flanges 23a of the brackets 23 into the doorway 11 and project through flanges 22a of the brackets 22. These pivot pins 24 tiltably support the door in the 45 doorway for swinging movement from the closed vertical position of Figure 1 to the open horizontal position of Figure 2. In the open position, the door 15 provides a canopy extending forwardly or outwardly from the doorway 11.

50. Brackets 25 are secured on the inner faces of the door jambs 12 in spaced relation beneath the brackets 23. These brackets 25 have inturned flanges 25a extending inwardly from the doorway 11. A toggle arm 26 is pivoted on each flange 25a through a headed pivot pin 27. The toggle arm 26, as shown, has an offset portion

55

26a extending laterally of the door jambs 12 to lie in overlapping relationship to the side edge of the door.

Additional brackets 28 are secured to the inner face of the door 15 adjacent the brackets 25 when the door is closed. These brackets 28 are riveted to the stile beams 17 and to horizontal beams 29 extending from the stile beams to the intermediate beams 21. The brackets 28 have a pair of inwardly extending ears or flanges 28a best shown in Figure 4. Arms 30 and 31 are respectively pivoted to these ears 28a by means of headed pivot pins 32. The arms 30 and 31 are in spaced relationship and provide the second link of the toggle linkage.

A fitting 33 is disposed between the arms 30 and 31 at the free ends thereof, and a pin 34 extends through all three arms 26, 30, and 31, with the portion 26a of the arm 26 lying between the arms 30 and 31. The arm portion 26a projects beyond the pin 34 as shown and has an outward flange or bent portion 26b on the free end thereof.

The pivot pin 34 extends through the fitting 33 and this fitting is swingable relative to the arms carrying the pin. The fitting has a spring retainer portion 33a between the arms 30 and 31 and a tension spring 35 has several of the end coils thereof fixedly engaged by the retainer portion 33a. This retainer can extend into several end coils of the spring and grip the coils as shown. The spring 35 has a bail type retainer 36 on the other end thereof. This retainer 36 is disposed over the pivot pin 24 inwardly of the bracket flange 22a and has swinging engagement therewith.

It will be appreciated, of course, that a toggle arm assembly composed of arms 30 and 31 pivoted on the door brackets 28, and an arm 26 pivoted on the door jamb brackets 25, together with a tension spring engaged between the fitting 33 and the pivot pin 24 is provided for each side edge of the door as shown in Figure 1. The springs 35 tend to pull the fittings 33 toward the pivots 24 thereby tending to spread the arm pivots 27 and 32 to open the arms and door to the position shown in Figure 2. In this position, the flange 26b of the arm 26 will strike against the adjacent arm 31 to prevent further movement of the arm toward an aligned position. The springs 35 thus act on the toggle arms to counterbalance the weight of the door and swing the door from its closed vertical position of Figure 1 to its open horizontal position of Figure 2. When the door is in the closed position of Figure 1, the fittings 33 are slightly beyond dead center positions with respect to the pivots 27 and 32 so that the springs 35, pulling upward on the fittings, are effective to pull the door to its fully closed position as shown in Figure 3. Dead center, or alignment of the fittings 33 with the pivots 27 and 32 so that spring action is directly against the pivots, occurs just before the door reaches closed position. However, when the door is swung manually outward beyond its dead center position, so that the fittings 33 are outwardly of the pivots 27, then the springs will become

effective to swing the arms for opening the door. Tension on the springs can be adjusted as desired by seating the retainers 33a and 36 at the desired spring coil, so that the door will be overbalanced by the springs as soon as it is manually swung to move the fittings 33 out of dead center positions relative to the arm pivots and the door pivots 24.

In order to prevent the arms from swinging too far inwardly from the inner face of the door when it is in closed position, a stop pin 37 is provided on the flange 25a of each bracket 25 to limit inward movement of the arms 26. This pin 37 effectively prevents inward swinging of the arms away from the inner face of the door when it is in closed position.

From the above descriptions it will be understood that the invention provides a closure construction wherein a door or other closure member is tiltably suspended on fixed pivots and is counterbalanced by spring-impelled toggles. These toggles have first arms pivoted to side jambs for the closure and second arms pivoted to the closure beneath the suspension pivots. The arms are pivoted together and springs under tension between the closure pivots, and the pivots connecting the arms tend to spread the arms apart, thereby moving the closure from a closed vertical position to an open horizontal position. The pivots connecting the arms with each other and with the side jambs and door are on dead center relative to the direction of spring pull just before the door is fully closed, so that the tension spring will pull the door to closed position on one side of dead center and to open position on the other side of dead center.

It will, of course, be understood that various details of construction may be varied through a wide range without departing from the principles of this invention and it is, therefore, not the purpose to limit the patent granted hereon otherwise than necessitated by the scope of the appended claim.

I claim as my invention:

In a tilting door assembly including means defining a doorway, a door for closing the doorway and means including at least one hinge pin for tiltably supporting the door in the doorway, a first toggle arm pivoted to the door, a second toggle arm pivoted to the doorway-defining means, one of said arms being bifurcated to provide two spaced portions, a transverse pivot pin between said portions, the other of said arms being pivoted to said pivot pin, and a spring connected at one end to the hinge pin and at the other end to said pivot pin.

LOWELL V. ROBINSON.
